The ornamental design for Christmas treetop ornament rotator, as shown and described.

DESCRIPTION

FIG. 1 is a perspective view of a Christmas treetop ornament rotator showing my new design;

FIG. 2 is a top plan view thereof;

FIG. 3 is a side elevational view thereof; and,

FIG. 4 is a bottom plan view thereof.

The broken lines in FIG. 1 showing an electrical connector and clip-type bracket attached to a tree limb, and the broken lines in FIGS. 2-4 showing an electrical connector are for illustrative environmental purposes only and form no part of the claimed design.
